PISTON STRUCTURE FOR UNIFLOW STEAM ENGINES

Everett C. Read, Milwaukee, Wis., assignor to
The Filer & Stowell Co., Milwaukee, Wis., a
corporation of Wisconsin

Application June 24, 1937, Serial No. 150,042

8 Claims. (Cl. 121—125)

This invention relates to an improvement in uniflow steam engines and more particularly to a novel means for floatably supporting the piston in the cylinder of such an engine.

5 In engines of this character it has been the practice to employ a floating piston, that is, one that does not bear against the cylinder wall, steam being prevented from passing the piston by one or more piston rings located in each end of 10 the piston. Such a floating piston is suspended on a piston rod which also floats through its packing and heretofore has been supported at one end by the main crosshead and at its other end by a slidable support or so-called tail cross- 15 head.

The present invention proposes to avoid the necessity of projecting both ends of the piston rod through the heads of the cylinder, the piston rod extending through one end only of the cylinder 20 for connection with the main crosshead. To accomplish this and yet still float the piston and the piston rod in the cylinder and in the stuffing box provided on one of the cylinder heads the present invention proposes to combine a slidable 25 support or crosshead with the piston itself, this slidable support being interposed between the spaced heads of the piston and riding on the lower portion of the cylinder wall.

Another object of the invention is to provide 30 an engine of this character which is simple and durable in its construction, reliable and efficient in operation and easy and comparatively inexpensive to manufacture and maintain.

Other objects and advantages reside in certain 35 novel features of the construction, arrangement and combination of parts which will be herein- after more fully described and particularly pointed out in the appended claims, reference being had to the accompanying drawing forming a part of 40 this specification, and in which:

Figure 1 is a fragmentary view in central vertical longitudinal section showing an engine embodying the present invention, parts being shown in elevation for the sake of illustration;

45 Figure 2 is a view in section taken on line 2—2 of Figure 1, parts being broken away for the sake of illustration;

Figure 3 is a detail view in top plan illustrating the face plate for the sliding shoe of the 50 piston support; and

Figure 4 is a diagrammatic view illustrating the type of engine with which the present invention is employed.

Referring to the drawing the numeral 5 designates the cylinder of a uniflow steam engine. A

5 piston rod 6 is reciprocable in the cylinder 5 and floats or slides freely through a stuffing box 7 provided in one of the end heads 8 of the cylinder. The outer end of the piston rod is connected and supported on the main crosshead 9.

A piston designated generally at 10 is assembled with the inner end of the piston rod and includes spaced piston heads designated at 11 and 12. The piston heads are of identical construction although oppositely arranged and each has a hub portion 13 suitably secured to the piston rod, a disk-like body portion 14 integral with the hub portion 13 and a peripheral skirt 15 integral to the outer portion of the body portion 14.

The peripheral surfaces 16 of the skirts 15 are 15 spaced slightly from the cylinder wall. Steam is prevented from passing the piston heads by means of piston rings 17 fitted in annular grooves 18 provided in the skirts 15 of the piston heads. The hollow space 19 of each piston head is closed 20 off by a cover plate 19', the edges of which may be welded to the hub and skirt of the piston head.

A supporting slide for the piston designated generally at 20 is located in between the piston 25 heads 11 and 12. This slide comprises a cast iron shoe designated at 21, formed at its ends with yoke-shaped cradles 22 and 23 in which the piston rod 6 rests. The underface of the body of the shoe 20 is flat as will be understood from a 30 comparison of Figures 1 and 2, and to this flat underface of the shoe a facing plate designated at 24 is applied. The upper surface of the facing plate 24 is also flat to have flush engagement with the undersurface of the shoe, but the lower 35 surface of this facing plate is transversely curved so as to conform to the contour of the lower portion of the cylinder wall. Preferably this facing plate is constituted of leaded bronze.

The central portion of the body portion of the 40 shoe is formed with a circular recess 25 and into this recess a correspondingly formed upwardly extending boss 26 of the facing plate fits. The facing plate, its boss 26 and the body portion of the shoe are provided with aligned bolt holes to accommodate a bolt 27 to which a nut 28 is applied to secure the parts assembled although leaving the facing plate free to adapt itself to riding contact with the lower portion of the cylinder wall.

The ends of the shoe 21 are formed with seats 50 29 which bear against the inner surfaces of the piston heads so that as the piston is reciprocated the supporting slide is constrained to movement therewith.

For the purpose of preventing angular dis- 55

placement of the supporting slide its cradles are provided with longitudinally aligned openings 30 through which a holding or retaining rod 31 extends. The end portions of this rod extend 5 through openings provided therefor in the piston heads and its extremities are riveted over into countersinks provided in the ends of the openings 31.

The supporting slide is dimensioned and proportioned to support or sustain the inner end of the piston rod throughout its stroke and do this in such manner as to maintain this piston rod properly centered. In other words, the inner end of the piston rod is precluded from sagging 10 under the influence of the weight of the piston so that the piston floats in the cylinder in the manner illustrated in Figure 1. The piston rod likewise floats through its stuffing box in the end head of the cylinder.

15 With the construction of this character it is unnecessary to provide a tail crosshead or to extend the piston rod through both ends of the cylinder. The construction of the engine is thus simplified and yet the piston and its piston 20 rod are floated in the cylinder and in the stuffing box respectively.

While I have shown and described one construction in which the invention may be advantageously embodied, it is to be understood that 30 the construction shown has been selected merely for the purpose of illustration or example and that various changes in the material size, shape and arrangement of the parts may be made without departing from the spirit of the invention or 35 the scope of the subjoined claims.

The invention claimed is:

1. An engine of the character described comprising a cylinder, a piston rod reciprocable in said cylinder, a piston on said rod having spaced 40 piston heads fixed thereto, the peripheral surfaces of said piston heads being slightly spaced from the wall of the cylinder, piston rings carried by said heads and having steam tight engagement with the wall of said cylinder, and a 45 supporting slide for the piston positioned in between said heads and riding on the lower portion of the wall of the cylinder and having direct supporting engagement with the piston rod intermediate said piston heads.

50 2. An engine of the character described comprising a cylinder, a piston rod reciprocable in said cylinder, a piston on said rod having spaced piston heads fixed thereto, the peripheral surfaces of said piston heads being slightly spaced 55 from the wall of the cylinder, piston rings carried by said heads and having steam tight engagement with the wall of said cylinder, and a supporting slide for the piston positioned in between said heads and riding on the lower portion 60 of the wall of the cylinder, and having cradles in which the piston rod rests and means connecting said slide to said heads.

3. An engine of the character described comprising a cylinder, a piston rod reciprocable in 65 said cylinder, a piston on said rod having spaced piston heads fixed thereto, the peripheral surfaces of said piston heads being slightly spaced from the wall of the cylinder, piston rings carried by said heads and having steam tight engagement with the wall of said cylinder, and a 70 supporting slide for the piston positioned in between said heads and riding on the lower portion of the wall of the cylinder, and having cradles in which said piston rod rests and a holding rod

extending through the cradles and secured to said heads.

4. An engine of the character described comprising a cylinder, a piston rod reciprocable in said cylinder, a piston on said rod having spaced piston heads fixed thereto, the peripheral surfaces of said piston heads being slightly spaced from the wall of the cylinder, piston rings carried by said heads and having steam tight engagement with the wall of said cylinder, and a 10 supporting slide for the piston positioned in between said heads and riding on the lower portion of the wall of the cylinder, and comprising a cast iron shoe having cradles in which said piston rod rests and a leaded bronze facing for 15 the shoe and contacting the cylinder wall.

5. An engine of the character described comprising a cylinder, a piston rod reciprocable in said cylinder, a piston on said rod having spaced piston heads fixed thereto, the peripheral surfaces of said piston heads being slightly spaced from the wall of the cylinder, piston rings carried by said heads and having steam tight engagement with the wall of said cylinder, and a 20 supporting slide for the piston positioned in between said heads and riding on the lower portion of the wall of the cylinder, and comprising a shoe in supporting relation to the piston rod and a 25 facing for the shoe floatably engaged therewith and bearing against the lower portion of the 30 cylinder wall.

6. An engine of the character described comprising a cylinder, a piston rod reciprocable in said cylinder, a piston on said rod having spaced piston heads fixed thereto, the peripheral surfaces of said piston heads being slightly spaced from the wall of the cylinder, piston rings carried by said heads and having steam tight engagement with the wall of said cylinder, and a 35 supporting slide for the piston positioned in between said heads and riding on the lower portion of the wall of the cylinder and comprising a shoe having cradles in which the piston rod rests and provided with a flat underside formed with a central rounded recess and a facing having a 40 flat upper face engaged with the flat underside of the shoe and provided with a rounded boss projecting into said recess and means pivotally connecting the boss to the shoe, said facing having 45 underside conforming in transverse curvature 50 to the cylinder wall.

7. An engine of the character described comprising a cylinder, a piston rod reciprocable in said cylinder, a piston on said rod having spaced piston heads fixed thereto, the peripheral surfaces of said piston heads being slightly spaced from the wall of the cylinder, piston rings carried by said heads and having steam tight engagement with the wall of said cylinder, and a supporting slide for the piston positioned in between said heads and riding on the lower portion 60 of the wall of the cylinder, and comprising a shoe engaged at its ends with the piston heads and having cradles in which the piston rod rests, a holding rod connected with said cradles and 65 said heads for preventing angular movement of the shoe, and a facing for the shoe engaged with the lower portion of the cylinder wall.

8. An engine of the character described comprising a cylinder having end heads, a stuffing box in one of said end heads, a piston rod floated through said stuffing box, a piston carried by the inner end of the rod and floated in said cylinder, said piston having piston rings for preventing steam from passing the ends thereof, a 70 75

main crosshead connected to and supporting the outer end of the piston rod, and a supporting slide riding on the lower portion of the wall of the cylinder, constrained to reciprocate with the piston and having supporting engagement with the inner end of the piston rod whereby the pis-

ton as well as the piston rod is floated in the cylinder and in the stuffing box respectively by virtue of the combined supporting action of said slide and said main crosshead.
